CIRCUMCISER

Augustus J. Baker, Cleveland, Ohio

Application June 21, 1941, Serial No. 399,099

2 Claims. (Cl. 128—305)

This invention relates generally to a surgical instrument commonly known as a circumciser, used in the surgical operation known as circumcision, which consists in removing a portion of the prepuce, leaving the glans penis exposed.

It is an object of this invention to generally improve upon the construction of the circumciser, and to produce a compact, convenient instrument of the kind which will facilitate making the operation more expeditiously in a minimum of time.

It is a further object of this invention to devise a circumciser which will permit advantageous combinations to be made by changing the parts so that the instrument may be used in practically all cases of circumcision from an infant to an adult, thus considerably widening its field of use.

It is a further object of this invention to provide a circumciser with means to carry a knife circumferentially around the cone or bell that shields the glans penis to sever the prepuce or foreskin at a predetermined plane.

Other features of the present invention will result from the following detailed description of a specific embodiment.

A preferred embodiment of the present invention will be hereinafter described with reference to the accompanying drawing, given merely by way of example, and in which similar reference numerals indicate similar parts in the several views, and in which:

Figure 1 is a vertical cross-section of an illustrative embodiment of the invention in which the knife carrying disk member is rotatably mounted on the base.

Figure 2 is a fragmentary front view of the instrument shown in Figure 1.

Figure 3 is a plan or top view of Figure 1.

Fig. 4 is a fragmentary front view of a ring and a penis shield, showing the indicia marked thereon, so that the ring and penis shield that goes with it may be easily selected by the operator.

Referring to the drawing in detail and to Figure 1 thereof in particular, there is shown a circumciser comprising a base 10 having integrally formed therewith an arm 11. In the base there is provided an aperture or hole 12 therethrough, and in the arm a smooth bore or journal 13. On the base there is a fixed ring member 14 having an extending annular flange 15. The ring is held in fixed position by means of screws 16. The knife carrying disk member 17 is held in assembled relationship by the fixed ring member and is rotatably mounted on the base. On the knife

carrying member there is provided a knife positioning member 18 in which the knife 19 may be adjusted, and after adjustment may be held in position therein by means of the set screw 20.

5 The knife carrying disk member is provided with a plurality of spaced knobs 21 by means of which it may be rotated on the base without causing rotation of the removably mounted ring in the base. The knife carrying disk projects 10 slightly over the base, and the edge 22 thereof may be knurled or milled so that the same may be digitally engaged to effect forced rotation thereof.

In the aperture or hole in the base there is provided 15 a removably mounted ring member 23 having an annular projecting flange 24 adapted to prevent the ring from slipping through the aperture or hole in the base. The ring is manually pressed into the aperture in the base and is held 20 by frictional contact therein. The ring also has an internally projecting flange 25 which prevents the shielding member from passing therethrough and also acts as a bearing for a portion of the shielding member when the prepuce is interposed 25 between the flange and the shielding member in the clamping operation. The aperture in the base is adapted to receive any one of a plurality of rings, each ring having an opening adapted to receive a shielding member that mutually cooperates 30 with the selected ring. The outside diameter of the various rings are made to a standard measurement, but the opening in the ring through which the shielding member nearly passes through, is dimensioned to receive the shielding member designed to go with the selected ring member. The shield and ring combination 35 may have numerals or other suitable identifying indicia or legends marked thereon to facilitate their proper selection. The identifying indicia is shown on the ring and also on the penis shield as at No. 1, however, any other suitable markings may be employed so that the combination 40 may be easily identified by the operator.

The shielding member 26 is of suitable configuration to receive the glans penis. The shield member is provided with a stem 27 having a threaded upper portion 28. The shield member may be provided with fenestrae, one of which is shown at 29 in Fig. 2, through which the position 45 of the glans penis may be observed in the shield member. The glans and prepuce are shown diagrammatically in the chain line in Fig. 1 at 42.

In the journal or bore in the arm there is mounted a non-rotatable axially movable control member 30. This member is provided with

an integrally formed head 31, a groove 32, and a threaded portion 33. Mounted on the member 30 there is a freely mounted internally threaded member 34. The aforesaid member is held in contact with the head 31 by means of a fixed collar 35. The internally threaded member is adapted to mechanically connect the shield member to the non-rotatable axially control member. The threaded portion of the control member cooperates with a threaded knurled nut 36 having a chamber so that rotation of the nut will cause an upward movement of the control member to which the shield member is attached. Interposed between the nut and the arm within the chamber there is provided a conical spiral spring 37 which is seated on the washer 38. The spiral spring can be compressed very short axially and tends to resiliently urge the control member with the connected shield member upward in the aperture in the base. A set screw 39 is provided in the arm, the end 40 of which engages the groove in the control member and prevents its rotation in the journal or smooth bore in the arm, but allows it to move up and down therein when the internally screwthreaded knurled nut is turned in the desired direction. The conical spring applies an upward movement to the member to which the shield member is connected, so that previous to the final clamping of the prepuce in the instrument, the shield may be slightly released in the base by pressing the member downward toward the base, thus freeing the shield member so that the position of the prepuce may be altered therein if desired, previous to the final clamping operation preparatory to the operation. The arm is provided with recesses or grooves 41 by means of which a grip on the instrument may be obtained.

The surgical operation as now performed is given for the purpose of comparison of the steps involved, and the steps eliminated by the use of the circumciser, as well as to disclose the simplicity of the operation when the circumciser is employed.

The operative technic of circumcision with the use of the instrument herein described is as follows:

The patient is placed on the examining table, the organ is given the usual preoperative treatment with an antiseptic and is then anesthetized. The proper shield is then selected. If the foreskin is irretractable, a dorsal slit is made in the foreskin or prepuce just long enough to allow the prepuce to be stretched over the shield. The shield member is then mounted in the instrument and the instrument is placed over the organ, the prepuce is then pulled up between the base and the shield member then up on the shield member,

and when properly positioned, the prepuce is clamped and crushed between the base of the instrument and the shield member thus causing haemostasis over all the blood vessels. The clamp is allowed to remain for a considerable length of time to prevent hemorrhage. The knife is then positioned and locked in the knife carrying member. The knife carrying member is then rotated, abscising the prepuce on an exact line with the top of the base of the clamp. The clamp is then removed, and should sutures be required, the surgeon inserts them where needed.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

What I claim as my invention and desire to secure by United States Letters Patent is:

1. In a device of the character described, comprising a support consisting of a base portion and an arm portion, each of the aforesaid portions having an aperture therein, a ring removably mounted in the aperture in the base portion, a shielding instrumentality extending into and partly through the ring and provided with a stem that is non-rotatable but axially movable in the aperture in the arm portion, and resilient means for imparting movement to the shielding instrumentality in the direction of the arm from the base.

2. A circumcision instrument comprising an arm portion and a base portion, each of the aforesaid portions having an aperture formed therein, a removably mounted ring having indicia marked thereon mounted in the aperture in the base portion, a penis shield identifiable by like indicia entering into and passing partly through the ring mounted in the base portion, a threaded portion connected to the penis shield non-rotatable but axially movable in the aperture in the arm portion, a knurled nut having a chamber formed therein, a conical spring mounted in the chamber and surrounding the threaded portion connected to the penis shield and adapted to urge the penis shield with its threaded portion connected thereto upward in the aperture in the base, a manually rotatable disk member mounted on the upper surface of the base member, means on the disk member for holding a knife, and means to permit adjustment of the knife therein relative to the penis shield.

AUGUSTUS J. BAKER.
